UNITED STATES PATENT OFFICE.

MAX BREMER, OF NEW BEDFORD, MASSACHUSETTS, ASSIGNOR TO THE PAIRPOINT MANUFACTURING COMPANY, OF SAME PLACE.

DESIGN FOR A CASKET-PLATE.

SPECIFICATION forming part of Design No. 25,095, dated January 28, 1896.

Application filed October 9, 1894. Serial No. 525,433. Term of patent 7 years.

To all whom it may concern:

Be it known that I, MAX BREMER, of New Bedford, in the county of Bristol and State of Massachusetts, have invented and produced a new and original Design for a Casket-Plate, of which the following is a specification, reference being had to the accompanying drawings, in which—

Figure 1 is a plan view, and Fig. 2 an end view, of a casket name-plate containing my new design. Fig. 3 is a plan view, and Fig. 4 an end view, of a casket ear-plate containing my new design.

The leading feature of my design consists in a curved margin fluted vertically in relation to the base and followed by a rising transverse swell, which is followed in turn by a transversely-ribbed space next a wide reverse scroll, which is followed by a curved margin that is fluted vertically in relation to the base, the two fluted margins being at opposite sides of the plate and the rising transverse swell having a surface ornamentation

of relief scrollwork, and the wide reverse scroll being surrounded by a relief-point and 25 pendent dropwork.

In the drawings, A is a curved margin vertically fluted relatively to the base, and B is a rising transverse swell which follows margin A.

C represents the ribbed space next swell B, and D is the wide reverse scroll, following which is a curved margin A', fluted like margin A. Bosses x, flanked by conventional scrollwork x', form relief ornamentation on scroll B, and round pointwork y and pendent dropwork y' form relief ornamentation along the sides of the wide reverse scroll D.

What I claim is—

The design for a casket-plate substantially 40 as herein shown and described.

MAX BREMER.
